Martha Harvey, INVENTOR
By Victor J. Evans

WITNESS:

ATTORNEY

UNITED STATES PATENT OFFICE.

MARTHA HARVEY, OF VANCOUVER, WASHINGTON.

UNDERGARMENT FASTENER.

Application filed August 13, 1927. Serial No. 212,786.

This invention relates to means for supporting undergarments on the body of a wearer, the general object of the invention being to provide a pair of straps, with means 5 for detachably connecting them to the various undergarments worn by a person so that it is not necessary to have a pair of straps attached to each undergarment, thus avoiding the necessity of having a number of 10 straps passing over each shoulder.

This invention also consists in certain other features of construction and in the combination and arrangement of the several parts, to be hereinafter fully described, illustrated in the accompanying drawings and specifically pointed out in the appended 15 claim.

In describing my invention in detail, reference will be had to the accompanying 20 drawings wherein like characters denote like or corresponding parts throughout the several views, and in which:—

Figure 1 is a front view, showing the invention in use.

25 Figure 2 is a view of one end of the device. Figure 3 is a longitudinal sectional view of Figure 2.

Figure 4 is a view similar to Figure 2, but showing a modification.

30 Figure 5 is an edge view partly in section of Figure 4.

Figures 6, 7, 8 and 9 are views showing various kinds of loops which may be used with the device.

35 Figure 10 is a rear view showing the invention in use.

As shown in these views, I use a pair of straps 1, one for each shoulder and to each end of each strap I attach a spring hook 2.

40 Each hook may be attached to its strap by means of the strap passing through an elongated eye 3 formed in the upper end of the hook, as shown in Figure 2, or I may provide means for detachably connecting the hook to the strap, as shown in Figures 4 and

5. In these views, 4 indicates a slotted bar which is passed through a hem formed in each end of each strap and 5 indicates a yoke which has hooks 6 at its ends for engaging the bar, as shown. A hook 7 is 50 swiveled to the center of the yoke.

Rings or loops are sewn to the upper edges of the undergarments to be worn, and loops of various shapes may be used for this purpose. Figure 6 shows a loop in the shape of 55 a ring 8, while Figure 7 shows an oblong loop 9. Figure 8 shows a substantially triangular shaped loop 10, with the point rounded, while Figure 9 shows a true triangular shaped loop 11.

60 From the foregoing it will be seen that when the undergarments are placed on the body, the hooks of the two straps are snapped in the loops at the upper edges of the garments, so that the one pair of straps will hold all the undergarments being worn. Thus but the one strap is used on each shoulder for supporting all the undergarments worn, and as many garments can be attached to the straps, as desired.

65 It is thought from the foregoing description that the advantages and novel features of my invention will be readily apparent.

I desire it to be understood that I may make changes in the construction and in the 70 combination and arrangement of the several parts, provided that such changes fall within the scope of the appended claim.

75 What I claim is:—

Means for holding undergarments on a 80 wearer comprising a pair of shoulder straps, each strap having a hem at each end thereof, a slotted bar passing through each hem, a yoke-shaped member having hooks on its limbs passing through the slot for connecting the yoke-shaped member with the bar and a hook swiveled to the central part of the bight of each yoke-shaped member.

85 In testimony whereof I affix my signature.

MARTHA HARVEY.
